CONTAINER OPENING DEVICE

August E. Almgren, Hillside, and John P. Jakob,
Roselle, N. J., assignors to American Can Com-
pany, New York, N. Y., a corporation of New
Jersey

Application June 28, 1949, Serial No. 101,870

8 Claims. (Cl. 226—129)

1

The present invention relates to a container filling or treating machine and has particular reference to devices for uncovering dispensing openings in closed empty containers preparatory to filling or otherwise treating the container.

An object of the invention is the provision in a container filling or treating machine of devices for lifting a closure element attached to fibre milk containers or the like wherein the closure element may be gripped and pried loose for bringing the gripped member into an open position.

Another object is the provision of such opening devices wherein suction instrumentalities may be used in conjunction with members utilized to grip the outer edges of a closure element so as to facilitate swinging of the gripped member in an open position.

Another object is the provision of such opening devices which are particularly adapted to release and lift closure members which are crimped or partially crimped around a projecting ledge or edge of a container and upon opening of the closure member to free the member for advancement of the container for subsequent treatment.

Numerous other objects and advantages of the invention will be apparent as it is better understood from the following description, which, taken in connection with the accompanying drawings, discloses a preferred embodiment thereof.

Referring to the drawings:

Figure 1 is a top plan view of an apparatus embodying the instant invention, with parts broken away and parts shown in section;

Fig. 2 is a view similar to Fig. 1 with additional parts broken away, and showing clearly a container in place in the apparatus;

Figs. 3 and 4 are vertical sections taken substantially along the lines 3—3, 4—4 in Fig. 1, with a container shown in place in the apparatus, and with portions of the container and parts of the apparatus broken away; and

Figs. 5 and 6 are enlarged fragmentary sectional views taken substantially along the lines 5—5, 6—6 in Fig. 1, with parts broken away and with the upper portion of a container in place.

As a preferred and exemplary embodiment of the instant invention the drawings illustrate an opening device for uncovering or unsealing the dispensing opening of a fibre container for liquids such as the container disclosed in United States Patent 2,085,979 issued July 6, 1937 to John M. Hothersall on Container. Such a container comprises a fibre tubular body A (Fig. 3) of rectangu-

2

lar shape and closed with top and bottom fibre members B and C (see also Fig. 5). The top member B, in one corner thereof, is formed with a circular filling and dispensing opening which is sealed with a friction plug closure element D (Fig. 5). This closure element is hingedly attached to the top member B.

In order to protect the top member B and its friction plug closure member D against injury or contamination during shipment and storage of the container, the entire top end of the container may be covered with an overcap E which is customarily creased and divided into two triangular shaped halves. Substantially one half of this overcap E (the triangular half disposed opposite the friction plug closure element D) is permanently secured by adhesive to the top member B. The opposite triangular half (marked F), hingedly connected by a crease line to the secured half, covers the portion of the top member containing the friction plug closure element and is free from the top member but is held in place by marginal edge portions G which extend over and are crimped under an overhanging or projecting edge or ledge H of the top member B.

In the manufacture of such a container, its interior is sterilized and the friction plug closure element D temporarily closed and sealed and the free portion F of the overcap E laid down and its marginal edge portion G temporarily crimped in place under the ledge H before the container is shipped to the dairy or filling plant for filling. At the filling plant the free portion F of the overcap E and the friction plug closure element D must be hinged open to effect the filling of the container through its filling and dispensing opening. In the instant case both the overcap and the closure element are lifted simultaneously into unsealed position. It is this opening or unsealing operation that is effected by the opening device of the instant invention.

The opening device preferably is a part of a more elaborate machine for handling the containers such as the machine disclosed in United States Patent 2,357,799 issued September 12, 1944 to A. E. Almgren on Container Handling Machine or the machine disclosed in United States Patent 2,284,660 issued June 2, 1942 to John M. Hothersall on Container Treating Machine.

In the devices shown in the instant drawings, the containers A disposed in an upright position as best shown in Fig. 3 are received from any suitable source and are propelled along a straight line runway 11 in a direction shown by the arrows 55 (Figs. 1, 2 and 4) in an intermittent or step-by-

step manner by a reciprocating feeding device having container propelling prongs 12 (Fig. 3) such as shown and fully described in the above mentioned Almgren Patent 2,357,799. The lower end of the container A is supported on a half-round support rail 14 and is guided by a pair of spaced and parallel guide rails 15, all of which are secured to the top of a horizontal frame 16 which may constitute a portion of the main frame of the more elaborate machine.

The upper end of the container is guided between a pair of spaced and parallel guide rails 17, 18 which are disposed above the rails 15. These upper guide rails 17, 18 are secured to an upper inverted U-shaped portion 19 of a bracket 20 bolted to the frame 16 adjacent the runway 11. The upper portion 19 of the bracket 20 overhangs the runway.

During a forward or container advancing stroke of the feeding prongs 12, a container A is advanced along the runway 11 one step and is brought to rest at an opening station K (Fig. 1). At this station the container is properly located in a predetermined position by a forward stop finger 23 (Figs. 1, 2, 4 and 5) which engages against the front or forward side wall of the container and by a rear stop finger 24 which engages over the rear top edge of the container.

The rear stop finger 24 is freely disposed above the path of travel of the container advancing in the runway 11 and hangs downwardly at an angle with its forward end in the path of travel of the container so that the advancing container engages and lifts the stop finger as the container passes under it. The forward end of the finger is formed with a notch 26 for engaging and locating the rear top edge of the container. Intermediate its ends, the stop finger 24 is freely mounted on a pivot pin 27 carried in a support block 28 adjustably secured by a locking screw 29 to an overhanging support bracket 31 bolted to the upper guide rail 18. By loosening the locking screw 29, the block 28 may be shifted in a groove 32 in the bottom of the bracket 31 to position the forward notched end of the stop finger 24 to properly locate the containers advanced into the station K. The block is locked in an adjusted position until another adjustment becomes necessary. The outer end of the stop finger 24 is formed with a hook lug 34 which engages against the back of the support block 28 to limit the downward travel of the stop finger when the container moves away from the finger after an opening operation as will be explained hereinafter.

The forward stop finger 23 which locates the container relative to its front or leading side, extends into the path of travel of the containers at an angle thereto (see Figs. 2 and 4) and is adjustably carried in a groove 36 formed in a support bar 37 fixed in a rotatable plate 38 in an eccentric position relative to the center of the plate. A locking screw 39 holds the stop finger 23 in adjusted position on the support bar 37. The plate 38 is formed on one end of a sleeve 42 (Fig. 1) which is journaled in a bearing block 43 supported on the frame 16. This plate is periodically rotated or rocked to shift the stop finger 23 into and out of container locating position.

Rotation of the plate 38 is effected preferably by a reciprocable rack bar 45 (Fig. 4) which meshes with gear teeth 46 formed on the periphery of the plate 38 for slightly more than one quarter of its periphery. The rack bar reciprocates in a slide bearing 47 formed on top of the

bearing 43 and overhanging the plate. Reciprocation of the rack bar may be effected in any suitable manner, as by a link 48 (Fig. 5).

Opening of the container A is effected by an opening head 51 (Figs. 1, 4, 5 and 6) which is located at the station K and immediately above the path of travel of the containers advanced into the station. This opening head 51 is formed on the free end of a long neck 52 which projects from the plate 38 in an eccentric position relative to the center of the plate. The center of the plate 38 is located in axial alignment with the hinge crease in the overcap E of a container A when the container is properly located at the station K (see Figs. 1 and 4). Hence when the plate 38 is rocked through an angle of 90° by the rack bar 45, the opening head 51 is similarly rocked relative to the top of a container at the station K.

The opening head 51 carries a resilient suction or vacuum cup 54 which is secured in place by a flat head screw 55 (Fig. 5) threaded into the head 51. The screw 55 is formed with an axially disposed channel 56 which communicates with a bore 57 formed in the head 51 and neck 52. The bore extends the full length of the neck and passes through the plate 38 and into the sleeve 42 for communication with a suitable source of vacuum, such as the pump and the accompanying slide valve disclosed and fully explained in the above mentioned Hothersall Patent 2,284,660.

Adjacent the vacuum cup 54, the opening head 51, carries a pair of spaced lifter fingers 61 which are disposed at right angles to each other as best shown in Fig. 1. These fingers are mounted intermediate their ends on pivot pins 62 (Fig. 6) carried in lugs 63 formed on the opening head 51. One end of each of the lifter fingers 61 as viewed in Fig. 6, extends below the vacuum cup 54 and is formed with a hook 65 having a tapered nose for engagement under the marginal edge portion G of the free section F of the overcap E. The opposite end of each of the fingers 61 curves inwardly over the opening head 51 and is engaged by a spring barrel 66 disposed within a blind bore 67 formed in the head. There is one of these spring barrels for each finger. Compression springs 68 disposed within the barrels force the latter outwardly against the fingers and thus maintain the hook ends of the fingers under pressure in a direction toward the opening head.

The hook ends 65 of the fingers 61 are maintained in a predetermined position relative to the head 51 by way of an adjustable stop member 71 disposed in a recess 72 in the finger and mounted on a pivot pin 73 secured in the finger. The outer end of the member is rounded and is engaged in one of two sockets 74 formed in a leaf spring 75 secured to the outer face of the finger. The inner end of the member 71 is also rounded and engages against one of two stepped faces 76, 77 of the opening head 51. By shifting the member 71 on its pivot pin 73, it may be made to engage against either the face 76 as shown in Fig. 6 or against the lower face 77. In this manner the fingers 61 may be adjusted to accommodate two kinds of containers in which the amount of overhang of the top member ledge H is different.

As a container A moves or advances into the opening station K, the rotatable plate 38 and the stop finger 23 and opening head 51 carried thereon are in the position shown in Fig. 5 (with the element D and overcap half F still is closed

5

position) the finger and the head being disposed above the path of travel so that the advancing container can readily move into the station without interference. Only the rear stop finger 24 has been engaged and raised by the entering container to permit the rear edge of the container to enter the locating notch 26 in the finger.

When the container A comes to rest at the station K, the plate 38 is rotated through an angle of 90° in a clockwise direction, as viewed in Fig. 5, and this effects three operations which take place simultaneously. Firstly, the front stop finger 23 is swung into a position in front of the container A where it engages the front wall of the container as best shown in Figs. 1, 2 and 4, and pushes the container backwardly so that its rear top edge is fully seated in the locating notch 26 of the rear stop finger 24. This action precisely locates the container in a predetermined position at the station K.

Secondly, the rotation of the plate 38 swings the lifter fingers 61 from the position shown in Fig. 5 to that shown in Fig. 6. During this swinging action the tapered noses of the fingers snap past the crimped edges G of the temporarily sealed overcap E and thus bring the finger hooks 65 into engagement with the edges G as shown in Fig. 6. In this position, the two fingers straddle the corner of the container adjacent its filling opening, there being one finger in engagement with each edge G of the free or unsecured triangular portion F of the overcap as best shown in Figs. 1, 2 and 4. A recess 81 (Figs. 1, 2 and 6) in the top guide rail 18 provides clearance for the adjacent lifter finger 61.

Thirdly, this rotation of the plate 38 rotates the vacuum cup 54 into engagement with the top outer face of the free triangular portion F of the overcap E as shown in Figs. 4 and 6. As soon as the vacuum cup is fully seated against the overcap, a vacuum is drawn on the cup to secure the cup to the engaged portion of the overcap. The plate 38 is then rotated through a return rotation of 90° in a counterclockwise direction (as viewed in Fig. 5) and thus returns or swings the front stop finger 23, the lifter fingers 61, and the vacuum cup 54, back into their original position as shown in Fig. 5.

During this return rotation of the plate 38, the front stop finger 23 is swung upwardly out of the path of travel of the container to free the container for further advancement. Simultaneously with this action the lifting fingers 61 with their hooks 65 frictionally engaged under the crimped edges G of the overcap E pry the edges G loose from the top member ledge H of the container and raise or lift these edges while the vacuum cup 54 hinges the free triangular portion F of the overcap into a raised or open position as shown in Fig. 5. During this overcap opening operation, the lifter fingers 61 press the edges G of the overcap, inwardly against closely adjacent edges of the friction plug closure element D and thus lift or hinge open the closure element simultaneously with the free portion of the overcap. Curved retaining shoes 82, 83 (Figs. 1, 2, 3 and 4) bolted to the upper guide rail 17 and the support bracket 31, respectively, and overhanging the top of the container hold the container against upward displacement during this prying loose of the crimped edges G and the lifting of the overcap portion F.

As the overcap portion F is hinged open, the closure element D becomes disengaged from the

6

edges G of the overcap and assumes an open position as shown in Fig. 5. When this overcap portion F is fully open as shown in Fig. 5, the vacuum in the cup 54 is broken and the cup is thereupon released from the overcap. The overcap is also released from the lifter fingers 61. For this latter purpose, the upper overhanging portion of each of the fingers is formed with an elongated button 85 (Figs. 1, 4, 5 and 6) which upon the return rotation of the plate 38, engages against a stationary tapered cam 86 and thereby rocks the hook ends of the fingers outwardly away from the overcap portion F and holds them in this position free of the overcap. This entirely releases the raised free portion F of the overcap. The cam 86 is adjustably secured by a locking screw 87 to the inverted U-shaped support 19.

With the raised free triangular portion F of the overcap E and the opened closure element D released from their opening devices, the container is immediately advanced through its next and succeeding steps toward the filling or other treating stations in the machine. During these steps of advancement the overcap portion F and the closure element D are maintained in their raised positions by a stationary guide rail 88 which is secured to the upper container guide rail 18 and which is engaged by the overcap portion F and the closure element D as the container is advanced. This completes the cycle of operation of opening the container for filling or other treatment.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for treating sealed containers having a filling opening closed by a cover and an attached overcap having a free portion superimposed over the cover and over said opening, the combination of a support for a container, propelling means for advancing said container in a predetermined path along said support, a rotatable plate disposed adjacent said support and path, a stop finger carried on said plate and movable into and out of said path of the container, an opening head extended from said plate and located adjacent said support, a lifter finger carried on said head, and actuating means for rotating said plate in one direction for moving said stop finger into said path and into engagement with said container for locating it in a predetermined position on said support and for simultaneously moving said lifter finger into engagement with an edge of the free portion of the overcap on the located container, said actuating means also rotating said plate in an opposite direction for moving said lifter finger away from said container for raising the engaged portion of said overcap and said cover to uncover the underlying portion of said container and for simultaneously moving said stop finger out of the path of said container.

2. In a machine for treating sealed containers having a filling opening and an attached overcap having a free portion superimposed over said opening, the combination of a support for a container, propelling means for advancing said

container in a predetermined path along said support, a rotatable plate disposed adjacent said support and path, a rear stop finger disposed in said path of the container and engageable with the trailing side of said container, a front stop finger carried on said plate and movable thereby into and out of said path, an opening head extended from said plate and located adjacent said support, a lifter finger carried on said head, and actuating means for rotating said plate in one direction for moving said front stop finger first into said path and against the leading side of said container, continued movement pushing the container against said rear stop finger to locate said container in a predetermined position on said support, said rotating plate simultaneously moving said lifter finger into engagement with an edge of the free portion of the overcap on the located container, said actuating means also being operable for rotating said plate in an opposite direction to move said lifter finger away from said container for raising the engaged portion of said overcap to uncover the underlying portion of said container, said rotating plate in said reversed movement simultaneously removing said front stop finger from the path of said container.

3. In a machine for treating sealed containers having a substantially rectangular top with a filling opening and friction plug closure element in one corner thereof and an attached overcap having a free portion superimposed over said closure element, the combination of a pair of spaced and angularly disposed lifter fingers arranged for straddling the corner adjacent said closure element of a container positioned for treatment, said fingers having hooked portions for engaging and holding two adjacent edges of the free portion of the overcap on said container, and means for moving said fingers simultaneously toward said container for engaging said edges of said overcap and for moving said fingers simultaneously in a reverse direction for lifting said free portion of said overcap and said closure element simultaneously to uncover the underlying filling opening in said container.

4. In a machine for treating sealed containers having a filling opening and an attached overcap having a free portion superimposed over said opening, the combination of a support for a container, propelling means for advancing said container in a predetermined path along said support, a rotatable plate disposed adjacent said support and path, a rear stop finger disposed in said path of the container and engageable with the trailing side of said container, a front stop finger carried on said plate and movable thereby into and out of said path, an opening head extended from said plate and located adjacent said support, a lifter finger carried on said head, actuating means for rotating said plate in one direction for moving said front stop finger first into said path and against the leading side of said container, continued movement pushing the container against said rear stop finger to locate said container in a predetermined position on said support, said rotating plate simultaneously moving said lifter finger into engagement with an edge of the free portion of the overcap on the located container, said actuating means also being operable for rotating said plate in an opposite direction to move said lifter finger away from said container for raising the engaged portion of said overcap to uncover the underlying portion of said container, retaining means adja-

cent the path of the top of said container for engaging said container top and thus restraining the container from upward movement while said overcap is raised, said rotating plate in said reversed movement simultaneously removing said front stop finger from the path of said container and means disposed adjacent said path of the container and engageable by the raised overcap for retaining the overcap in its raised position.

5. In a machine for treating containers each having a closure for a container filling opening and terminating in an edge adjacent a projecting container ledge and also having an overcap of flexible material extending over said closure and loosely crimped at its marginal edge over said projecting container ledge, the combination of an opening head movable toward and away from a container positioned thereadjacent, a vacuum cup carried on said head and engageable with said overcap, a yieldable lifter finger carried on said head alongside of said vacuum cup and engageable with the loosely crimped marginal edge of said overcap on said container to yieldably press said edge of the flexible overcap inwardly, means for moving said head toward said container for engaging said vacuum cup and said finger with said overcap and for moving said head and its vacuum cup and finger away from said container for first removing said yieldably pressed marginal edge of the overcap from the container ledge and then for engaging said inwardly pressed flexible edge of the overcap against a closely adjacent edge of said closure whereby said overcap and said closure are moved together to uncover said opening, and means for releasing said vacuum cup and lifter finger from said overcap when the latter is raised.

6. In a machine for treating containers each having a closure for a container filling opening and terminating in an edge adjacent a projecting container ledge and also having an overcap of flexible material with a free portion extending over said closure and loosely crimped at its marginal edge over said projecting container ledge, the combination of an opening head, a vacuum cup carried on said head and engageable with the free portion of said overcap, a lifter finger carried on said head adjacent said vacuum cup and engageable with the loosely crimped marginal edge of the free portion of said overcap to engage and press said flexible edge inwardly, and means for effecting relative movement between said head and said positioned container for causing said vacuum cup and said finger to release said loosely crimped marginal edge of the overcap from the container ledge and, through the pressure applied inwardly by said lifter finger against said flexible marginal edge of the overcap, to engage said marginal edge with said edge of the closure whereby the overcap and the closure are moved together to uncover said opening.

7. In a machine for treating containers each having a closure for a container filling opening and terminating in an edge adjacent a projecting container ledge and also having an overcap of flexible material with a free portion extending over said closure and loosely crimped at its marginal edge over said projecting container ledge, the combination of a runway for supporting and guiding a container along a predetermined path of travel, advancing means engageable with said container and intermittently advancing the container along said runway, locat-

ing means adjacent said runway and engageable

with a container at rest in said runway for locating the container in a predetermined position, a vacuum cup rotatably mounted adjacent said runway and the path of said overcap for engagement with the free portion of the overcap on a said located container, a yieldable lifter finger rotatably mounted adjacent said vacuum cup for engagement with the loosely crimped marginal edge of the free portion of said overcap on said located container to yieldably press said edge of the flexible overcap inwardly, and actuating means for rotating said vacuum cup and said lifter finger simultaneously into engagement with said free portion of the overcap and for rotating said vacuum cup and said lifter finger simultaneously in a reverse direction for removing said yieldably pressed marginal edge from the container ledge and then for engaging said inwardly pressed flexible edge of the overcap against a closely adjacent edge of the closure whereby said overcap and said closure are moved together to uncover said opening.

8. In a machine for treating sealed containers having a filling opening and an attached overcap having a free portion superimposed over said opening, the combination of an opening head movable toward and away from a container positioned thereadjacent, a lifter finger yieldably mounted on said head and engageable with an edge of the free portion of the overcap on said

5
10
15

container, a plurality of stepped surfaces on said head adjacent said lifter finger, an adjustable stop member movably mounted on said lifter finger, the inner end of said member engaging one of said stepped surfaces on the head in a predetermined position for precise engagement with the edge of said overcap, means for retaining said inner end of the stop member in alignment with a selected stepped surface, the selection of said surface being dependent upon the size of said container, and means for moving said head toward said container for engaging said finger with said overcap and for moving said head and its finger away from said container for raising the free portion of said overcap to uncover the underlying portion of said container.

AUGUST E. ALMGREN.
JOHN P. JAKOB.
